UNITED STATES PATENT OFFICE.

JOHN A. SEEDE, OF SCHENECTADY, NEW YORK, ASSIGNOR TO GENERAL ELECTRIC COMPANY, A CORPORATION OF NEW YORK.

ELECTRIC FURNACE.

Application filed February 13, 1925. Serial No. 9,033.

My invention relates to electric furnaces of the induction type, and has for its object the provision of a furnace of this type which may be operated on a polyphase electric supply source.

More particularly my invention relates to electric induction furnaces for melting metals which are provided with a looped channel in which a portion of the molten charge forms a closed secondary, and in which circulation of the molten charge is produced by electromagnetic repulsion between the primary winding and the portion of the charge forming the secondary. Such a furnace is shown, for example, in a co-pending application of James M. Weed, Serial No. 525,660, filed December 29, 1921, assigned to the same assignee as this invention, of which this invention is an improvement.

In carrying out my invention I provide a plurality of primary windings which may be connected to a polyphase electrical supply source. These primary windings are inductively related to a branched molten secondary, and are arranged with relation to the secondary so as to produce a circulation of charge by means of electromagnetic repulsion.

For a more complete understanding of my invention reference should be had to the accompanying drawing in which Fig. 1 is a vertical section view of an electric induction furnace embodying my invention; Fig. 2 is a section view along the line 2-2 of Fig. 1, looking in the direction of the arrows; Fig. 3 is a reduced perspective view of the furnace shown in Figs. 1 and 2; while Fig. 4 is a diagrammatic view showing the connections for the primary windings.

Referring to the drawing, I have shown my invention in one form as embodying a refractory furnace crucible 10 which is shaped or moulded to provide an upper reservoir 11 for the molten charge 12, and a lower looped channel 13 which communicates with the reservoir at a central region through a central port or duct 14 and at axially remote regions through two ports or ducts 15 and 16 at the axial extremities of the channel. As shown, the channel 13 is cylindrical or annular in shape, although it may have various other suitable shapes, and forms a closed loop entirely independent of the reservoir.

The crucible 10 may be formed in any suitable manner, for example, by tamping the plastic material from which the crucible is made around a suitable core. If it is desired, the crucible may be built up from pre-formed parts which are cemented together. 60

At its lowermost portion the channel 13 is divided into two branches 17 and 18 whereby an aperture 19 is provided in the crucible for a central leg of a magnet core 20. This core also extends through an aperture 21 provided in the crucible, which aperture is substantially concentric with the channel 13, and completely encircles the two branches 17 and 18 of the channel. 70

On the core 20 are two primary windings 22 and 23. These primary windings are inserted in opposite ends of the aperture 21 in the crucible, and have their axes substantially coincident with the axis of the channel 13. They are positioned axially so that their centers are on opposite sides of the center of the channel 13, and likewise on opposite sides of the central port 14. As shown, the winding 22 has its center spaced 80 somewhat to the left, while the winding 23 has its center spaced somewhat to the right of the center of the channel. 75

Various connections may be used between the primary windings 22 and 23 and the source of supply. When operating on a three-phase source of supply the well known Scott connection may be used as indicated in Fig. 4 in which one terminal of the winding 22 is connected to a central tap 24 on the other winding 23 which is provided with a greater number of turns. The remaining terminals 25, 26 and 27 of the windings are connected to a three-phase source of supply 28. With this connection the currents induced in the respective ends or branches of the molten secondary in the channel 13 are displaced 90° in phase with respect to each other. Where suitable two-phase current is available, the primary coils may be connected directly to the source of supply. 90

The refractory crucible 10 is preferably enclosed in a protecting metallic casing 29. A spout 30 is provided through which the charge may be poured from the reservoir, for example, by tilting it on a suitable support. The top of the reservoir is preferably closed by a cover 31. 105

In its operation the furnace may be started by pouring in a sufficient quantity 110

of molten charge to fill the channel 13, whereby the channel forms a short circuited secondary for the primary windings 22 and 23. Heat is then generated by the induced currents in the closed secondary, any additional charge may be melted by putting it in the reservoir 11. Due to the axial position of the primary windings 22 and 23, electromagnetic repulsive forces will be exerted on the molten secondary tending to force it from each end of the channel 13 in an axial direction towards the centre. The molten secondary will be pushed toward the right by the winding 22, and toward the left by the winding 23. This results in an increase in pressure in the central portion of the molten charge whereby the charge is forced upward through the port 14 into the reservoir. The charge is free to return to the channel 13 from the reservoir through the two end ports 15 and 16. It will thus be observed that a circulation of charge will be set up in an axial direction through the secondary channel to the reservoir, and from the reservoir back to the channel. The charge also has a certain amount of flow in a circumferential direction in the channel, particularly in regions in the vicinity of the axial center of the channel. In other words, the molten charge in a central circumferential zone of the channel has a somewhat circumferential direction of flow in passing from regions of high pressure to the region of lower pressure at the port 14 through which the molten charge escapes.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. An induction furnace comprising a crucible forming a reservoir for the charge and a looped channel communicating with said reservoir, and a plurality of primary windings inductively associated with said channel for inducing heating currents in a conductive charge in said channel, said primary windings being so placed with respect to said channel that oppositely directed electromagnetic repulsive forces are exerted by said primary windings respectively on the portion of the charge in said channel whereby a circulation of molten charge is produced between said reservoir and said channel.

2. An induction furnace comprising a refractory crucible forming a reservoir for the charge and a looped channel in which a

portion of the charge forms a closed secondary, said channel being connected with said reservoir at a central region and at regions spaced axially from said central region, and a plurality of primary windings inductively arranged with respect to said channel so as to produce a circulation of molten charge by electromagnetic repulsion between said reservoir and said channel, said charge passing through said central region in one direction and through said axially spaced regions in an opposite direction.

3. An induction furnace comprising a refractory crucible forming a reservoir for the charge and a looped channel in which a portion of the charge forms a closed secondary, said channel being connected with said reservoir at a central region of said secondary and at axially remote regions of said secondary, and a pair of primary windings inductively related to said secondary displaced axially from said central region, whereby electromagnetic repulsive forces are exerted on said secondary producing a circulation of molten charge between said reservoir and said channel having a common path through said central region.

4. An induction furnace comprising a refractory crucible forming a reservoir for the charge and a looped channel in which a portion of the charge forms a closed secondary, said channel being connected with said reservoir at a central region, and at two regions axially remote therefrom, and a pair of primary windings inductively arranged to exert repulsive forces on said secondary tending to force the molten metal from the axial extremities of said channel toward said central region whereby the molten charge is caused to circulate between said channel and said reservoir.

5. An induction furnace comprising a refractory crucible forming a reservoir for the charge and a looped channel in which a portion of the charge forms a closed secondary, said channel being connected with said reservoir at a central region and at two axially remote regions, a magnet core interlinking said channel, and a pair of primary windings on said core spaced in opposite directions from the center of said channel whereby the molten charge is forced by electromagnetic repulsion out of said channel into the reservoir through said central region, the charge returning from the reservoir to the channel through said axially remote regions.

6. An induction furnace comprising a refractory crucible forming a reservoir for the charge and an annular channel communicating with said reservoir through a central and two axially remote ports, a magnet core interlinking said channel, and two primary windings on said core situated on opposite sides of said central port whereby a repulsive force is exerted tending to force the

- molten charge axially from the ends of said channel through said central port into said reservoir, the charge returning to said channel through said axially remote ports. 25
- 5 7. A polyphase induction furnace for melting metals comprising a refractory crucible forming a reservoir for the charge and an annular channel in which a portion of the charge forms a closed secondary, said crucible providing a port connecting central regions of said reservoir and said channel and axially remote ports connecting the ends of said secondary with said reservoir, a magnet core interlinking said channel, a pair of primary windings on said core inserted in said channel and a polyphase source of supply for said primary windings, said primary windings being spaced axially of said channel adjacent the ends thereof so as to exert 30 electromagnetic repulsive forces on said secondary and thereby force the molten charge axially from the ends of said channel through said central port into said reservoir, 35
- 10 15 20
8. An induction furnace comprising a crucible forming a reservoir for the charge and a looped channel communicating with said reservoir at central and axially remote regions, said channel being divided into two branches, a magnet core encircling the branches of said channel, a plurality of primary windings on said core for inducing heating currents in a conductive charge in said channel, and a polyphase electric supply source for said windings, said windings being so placed with respect to said channel that oppositely directed electromagnetic repulsive forces are exerted on the portion of the charge in said channel so that a circulation of molten charge is produced between said reservoir and said channel through said central and axially remote regions. 40

In witness whereof, I have hereunto set my hand this 12th day of February, 1925.

JOHN A. SEEDE.
